UNITED STATES PATENT OFFICE.

JAMES S. GILDAY, OF BLAINE, WASHINGTON.

AIR JACK.

Application filed March 11, 1921. Serial No. 451,469.

To all whom it may concern:

Be it known that I, JAMES S. GILDAY, a citizen of the United States, residing at Blaine, in the county of Whatcom and State 5 of Washington, have invented a new and useful Air Jack, of which the following is a specification.

This invention relates to jack constructions, and more particularly to a fluid 10 operated jack to be employed in connection with motor vehicles or the like.

The primary object of the invention is to provide a jack of this character which will be operated by fluid pressure admitted to a 15 cylinder in which the lifting element is positioned.

A further object of the invention is to provide a novel form of valve construction 20 to be used in connection with the jack for controlling the passage of air to and from the cylinder of the jack.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:—

Figure 1 illustrates a vertical longitudinal sectional view through a jack constructed 35 in accordance with the present invention.

Figure 2 illustrates a plan view of the same.

Figure 3 illustrates a sectional view taken on line 3—3 of Figure 1.

40 Referring to the drawing in detail, the reference character 5 designates the body portion of the jack which is bored to provide a cylinder 6, the cylinder being closed at its upper end as by means of the head 7, which 45 carries a nut 8 for securing the packing 9 to the head, for insuring a fluid-tight connection between the lifting rod 10, and the head 7.

The body 5 also includes a base 11 which 50 has a portion thereof extending laterally beyond the side wall of the body portion 5 to provide a foot rest whereby the jack will be insured against lateral movement when the same is in operation.

55 Forming a part of the body portion 5 is an enlargement 12, which is bored to pro-

vide a passageway 13 communicating with the cylinder 6 through the passageway 14. At the base of the body portion is a passageway 15 providing communication between the bore 16 and cylinder 6, so that air may enter the cylinder 6 through the bore 16 and passageway 15.

Communicating with the passageway 13 and bore 16, is a valve casing 17, there being provided relatively short pipes 18 and 19 for establishing the communication between the valve casing 17 and passageway 13 and bore 16. Operating within the valve casing 17 is a valve member 20 provided 70 with an operating handle 21 formed at the upper end thereof, and by means of which the valve member may be moved within the casing.

This valve member is provided with openings 22 and 23, designed to register with openings in the wall of the valve casing. The valve member is provided with a central passageway 24 designed to communicate with the pipes 18 and 19 respectively, so that when the valve member is moved to predetermined positions, communication will be established between the cylinder 6 and valve casing.

The valve nipple 25 extends laterally from the valve casing 17 and provides means for connecting the supply tube to the body portion of the jack to admit air to the valve casing, and to the cylinder 6.

This nipple 25 is arranged substantially centrally of the valve casing 17 in which the valve member 20 moves, the valve member 20 being provided with spaced openings 20' and 21' which openings are designed to register alternately with the nipple 25.

A piston indicated at 26 is carried at the lower end of the lifting rod 10, the piston being provided with suitable packing 27 to insure a fluid-tight connection between the walls of the cylinder 6 and piston to insure the lifting rod receiving the entire force of the incoming fluid.

At the opposite end of the connecting rod 10 is a head 28 to engage under an axle or the like, for preventing slipping of the jack with respect to the device being lifted.

In the operation of the device, with the valve member 10 in the position as indicated by Figure 1, it will be seen that as air is forced into the bore 16 and into the cylinder 6, the air contacts with the piston to

force the same upwardly, the air which is within the upper portion of the cylinder 6 being forced outwardly through the passageways 14, 13 and opening 22.

5 Upon the reverse movement of the rod 10, the valve is moved until the central passageway communicates with the pipe 18, which brings the openings 23 in communication with the pipe 19 to permit the air contained in the lower portion of the cylinder 6 to be exhausted therethrough.

Having thus described the invention, what is claimed as new is:—

10 In a fluid actuated jack, a cylindrical body portion said body portion having passageways extending longitudinally thereof and in communication with the upper and

lower ends of the cylindrical body portion, a tubular valve casing in communication with the passageways, and having a hollow valve mounted therein, said hollow valve having openings extending transversely thereof to establish communication between the passageways and atmosphere, and a valve nipple communicating with the hollow valve to direct air to the passageways.

20 In testimony that I claim the foregoing as my own, I have hereto affixed my signature in the presence of two witnesses.

25 JAMES S. GILDAY.
